DICTATION MASK WITH CARTRIDGE TYPE SILENCER

Filed Sept. 1, 1948

UNITED STATES PATENT OFFICE

2,572,547

DICTATION MASK WITH CARTRIDGE
TYPE SILENCER

Horace L. Webb, Vienna, Va.

Application September 1, 1948, Serial No. 47,199

6 Claims. (Cl. 179—188)

1

This invention relates to a device or mask for use in court reporting assemblies or other gatherings to receive directly the uttered or other sound in such manner as to be non-disturbing to participants, spectators or other persons, being generally like, following the principles of, and an improvement over the device disclosed for instance in my co-pending application, Ser. No. 667,827, filed May 7, 1946, now Patent No. 2,526,177, granted October 10, 1950.

A prime object is to provide a construction better enabling the employment of ambient sound and moisture-absorbing means in the form of a readily renewable cartridge.

A second object is to provide such a cartridge in shape-retaining form.

A third object is to provide a novel casing which especially co-acts with the sound and moisture-absorbing cartridge so that maximum space within the body will be filled thereby and centering of the cartridge aided.

The fourth object is to provide a novel construction which avoids interference of the sound and moisture-absorbing material with the switch or operation thereof.

Various additional objects and advantages will become apparent as the description proceeds.

In the accompanying drawings illustrating one operative embodiment:

Fig. 1 is a perspective view of the improved dictating mask as held in operative position by a hand suggested in dotted lines;

Fig. 2 is a side elevation of the mask in open condition with a sound and moisture absorbing cartridge about to be inserted; and

Fig. 3 is a central vertical sectional view taken longitudinally through the mask.

Referring specifically to the drawings wherein like reference characters designate like or similar parts, 9 designates a casing or body of any suitable length, shape and material, such as modern plastic, or metal like aluminum or magnesium, in view of its light weight or otherwise and in any approved size and for example consisting of sections 10 and 11. The former is hollow and generally cylindrical for the passage of sound therethrough, and the latter is a normally closed end therefor. Closure section 11 is displaceable, being either detachable or removable, or, as shown, hinged at 12 to coating lugs 13 and 14 fastened respectively to section 10 and an annular marginal rim 15 of closure section 11. One or more spring-metal or plastic clips 16 on section 10 have latching engagement with said rim 15 to normally prevent opening of the casing. At the open dictation end of the section 10, it is flared somewhat at 10a and wedged therein is a flexible rubber diaphragm-like face piece or sound receiver 17 similar or equivalent to that disclosed at 14 etc. in my aforesaid application Ser. No. 667,827, Rivets 10b or a bonding cement or both may be used to secure receiver 17 within said flare 10a and aid in sealing the junction airtight. Sound receiver 17 contacts and fits the face of a dicta-

2

tor and surrounds and encloses the mouth or nose and carries a microphone 20 at any suitable location. As in said pending application the face-piece or sound receiver 17 carries a relatively thin flange 17a (like 16 in said pending application) extending around and inwardly from the periphery contacting and fitting the face of a dictator surrounding and enclosing the mouth and nose and the cheek-bones to absorb or tend to absorb sounds vibrating through such bones.

Conductors 19 operatively connect said microphone to a conventional dictating machine, and one of which conductors is preferably grounded to such machine. A conventional switch 22, 15 through the conductors 23, one of which may be grounded, controls the operation of the said dictating machine, and such conductors 21 and 23 are suitably covered or protected and pass through a guiding and wear-reducing grommet 24 in the wall of section 10. Said receiver 17 above the microphone 20 has a suitable number of breather openings 24 therethrough.

Section 10 is filled with an ambient sound and moisture absorbing mass, for instance, of celulose material, felt, or any suitable equivalent M, preferably in the form of a cartridge which is shape-retaining and thus capable of more expeditious handling. This cartridge M is shown to best advantage in Fig. 2, wherein closure 11 is 30 open with respect to the section 10 and the cartridge M is about to be inserted into the section 10 through the available end thereof. In order to render mass M shape-retaining, it is preferably dipped into a starch solution, a plastic solution or any equivalent, and then dried. This readily removable and replaceable cartridge completely fills the available space in the section 10 behind the sound receiver 17. Note that the shape-retaining nature of the cartridge provides 40 a depression in the adjacent end of the cartridge M, which interfits with the receiver 17. In the section 10 between the diaphragm and the cartridge, a sheet of air penetrable metallic or plastic gauze 26 is disposed, preferably being 45 cemented at its marginal edge to the section 10. The conductors 19 and 23 are sufficiently slack to closely lie against the wall 19 and rim 15, thus enabling free opening of closure 11 and ready and frequent replacement of the cartridge 50 M in the aid of sanitation.

The aforesaid rim 15 abuts the rear end of the cartridge M and will assist in moving the latter into position if not accurately applied. This feature is augmented by the rabbetting at 27 of 55 a marginal edge of the rim to enable it to slightly telescope into the section 10.

Extending integrally from rim 15 is a hollow knob-like projection 28 which carries a bracket 29 therein directly mounting switch 22. Such 60 switch is preferably of the type having a depressible actuator 30 including a plastic or other fingerpiece 31, which is guided in and normally projects above an opening 32 in the upper wall of the knob 28. This fingerpiece is wedge-shaped

in cross-section and normally closes opening 32, but as it is narrowest at its top, the depression will partly uncover opening 32 to function as a breather opening.

It will be noted that rim 15 forms an abutment to movement of the cartridge or other mass M toward the switch 22, and that the latter is so mounted that there will be no interference between the same and mass or cartridge M.

In using the device it is grasped in one hand by the knob 28, as suggested by the dotted lines in Fig. 1, and talked into while the sound receiver 17 is held against the face, surrounding the chin, mouth and nose, sound being transmitted through the microphone to the talking-machine, ambient sound however being muffled and absorbed within the casing and prevented from passing to the exterior by the cartridge M. The finger-piece 31 is readily manipulated by one finger of the hand which grasps the knob 28, and when depressed partly uncovers opening 32 so that the latter functions as a breather opening.

Whenever desired, the closure 11 may be moved on its hinge 12 to and from open position, disengaging and engaging the latch 16, to facilitate replacement of the cartridge M, which is advisable from time to time because of moisture absorption.

Various changes may be resorted to provided they fall within the spirit and scope of the invention.

I claim:

1. A dictating device comprising a two-ended body having one end open to receive sound, a displaceable closure at the other end of the body, an electric microphone and a control switch in said body, electric current conducting means connected to said microphone through said switch, a sound-absorbing filler in the body applicable and removable when the closure is displaced, a flexible diaphragm-like receiver outwardly enlarged with respect to the other end of said body, closing the latter end, said microphone being carried by said receiver, a flexible face-fitting flange on the interior of said receiver, said control switch being mounted by said closure and said closure having a portion interposed between said filler and said switch to prevent interference of the filler with operation of the switch.

2. A dictating device comprising a two-ended body having one end open to receive sound, a displaceable closure at the other end of the body, a control switch carried by said closure and removable from the exterior thereof, an electric microphone in said body, electric conducting means connected to said microphone through said switch, a sound-absorbent cartridge in the body of shape-retaining characteristic, said cartridge being applicable and removable when the closure is displaced, and said closure means abutting said cartridge and maintaining it out of interfering relation with said switch.

3. A dictating device comprising a two-ended body having one end open to receive sound, a displaceable closure at the other end of the body, an electric microphone and a control switch in said body, electric current conducting means connected to said microphone through said switch, a sound absorbing cartridge in the body, a sound receiver in the open end of said body, said receiver and closure having openings to enable breathing through said cartridge, said cartridge having a depression interfitting with

said sound receiver, said switch being carried by said closure and said closure having a portion abutting said cartridge and maintaining said cartridge out of interfering engagement with said switch.

4. A dictating device comprising a two-ended body having one end open to receive sound, a flexible sound receiver closing the open end of said body and outwardly enlarged with respect thereto, a closure at the other end of the body, an electric microphone carried by said sound receiver, a control switch, electric current conducting means connected to said microphone through said switch, a sound-absorbing filler in the body applicable and removable through the said open end when the closure is displaced, said closure having a hand-grasping portion carrying said switch and forming an abutment for said filler to space the latter out of interfering relation with said switch.

5. A dictating device comprising a two-ended body having one end open to receive sound, a flexible sound receiver closing the open end of said body and outwardly enlarged with respect thereto, a closure at the other end of the body, an electric microphone carried by said receiver and a control switch in said body, electric current conducting means connected to said microphone through said switch, a sound-absorbing filler in the body interfitting with said sound receiver, said closure being in displaceable relation with respect to the body and having a rim extending partly across the adjacent end of the body, and a hollow knob-like outward extension on the closure, said switch being mounted on said extension and maintained out of interfering relation with the filler by said rim.

6. A dictating device comprising a double-ended dictating body, an electric microphone within said body, a sound-absorbing filling in the body, a closure means hinged to one end of the body, a rim on said closure means extending partly across one end of the device, an outwardly extending hollow knob-like extension on the closure having an opening to enable breathing therethrough, a control switch within said extension, said rim preventing interference of said filler with said switch, said switch having a finger-piece slidable in said opening, and said body having an opening, conductor means passing through said latter opening to said microphone and switch.
